DESIGN FOR A DIAPER OR SIMILAR ARTICLE

Narcisse Cadgène, Montclair, N. J.

Application November 12, 1941, Serial No. 104,115

Term of patent 3½ years

To all whom it may concern:

Be it known that I, Narcisse Cadgène, a citizen of the United States, residing at 402 Upper Mountain Avenue, Montclair, county of Essex, State of New Jersey, have invented a new, original, and ornamental Design for a Diaper or Similar Article, of which the following is a specification, reference being had to the accompanying drawing, forming part thereof,

I claim:

The ornamental design for a diaper or similar article, as shown.

NARCISSE CADGÈNE,
